Primary Examiner—Doris Clark**[57] CLAIM**

The ornamental design for a combined header and sill frame component for a window or door, as shown and described.

DESCRIPTION

FIG. 1 is a perspective view of the combined header and sill frame component for a window or door; and,

FIG. 2 is an end view of the combined header and sill frame component for a window or door.

The combined header and sill frame component for a window or door of FIG. 1 is broken away to indicate indefinite length.
